RAZOR SHARPENER.

Thomas M. Page, Detroit, Mich.

Application March 28, 1947, Serial No. 737,764.

9 Claims. (Cl. 51—156)

1

This invention relates to razor sharpeners, and more particularly to a device for honing and stropping a safety razor blade.

An object of the invention is to provide a razor sharpener wherein a safety razor blade is drawn across a hone by magnetic action.

A further object of the invention is to provide a razor sharpener wherein the razor blade is drawn across a concave hone under magnetically controlled pressure.

A further object of the invention is to provide a razor sharpener wherein the angle of the blade relative to the hone is automatically controlled.

A further object is to provide a honing apparatus wherein the magnetic flux cooperates with the honing action in bringing the minute serrations of the razor edge into alignment with each other.

A further object of the invention is to provide a honing apparatus wherein a permanent magnet draws a safety razor blade across a concave surface of a hone and simultaneously holds it in contact therewith under controlled pressure.

Further objects and advantages of the invention will be apparent from the following description, taken in connection with the appended drawing, in which:

Fig. 1 is a perspective view of a razor sharpener embodying the invention;

Fig. 2 is a plan view of the same;

Fig. 3 is a vertical sectional view of the same, taken on the line 3—3 of Fig. 2;

Fig. 4 is a horizontal section of the same, taken on the line 4—4 of Fig. 3;

Fig. 5 is a sectional view similar to Fig. 3 but showing a modified form of the device; and

Fig. 6 is a similar view of a further modified form.

It is to be understood that the invention is not limited in its application to the details of construction and arrangement of parts illustrated in the accompanying drawing, since the invention is capable of other embodiments and of being practiced or carried out in various ways. Also it is to be understood the phraseology or terminology employed herein is for the purpose of description and not of limitation.

The device shown in Figs. 1—4 comprises a frame made up of end pieces 10 and 11, provided with inturned flanges designated 12 and 13 respectively.

The end pieces 10 and 11 may be formed of wood or other suitable material, and are connected by means of bolts 16 and 17, which pass through suitable apertures in the end pieces.

Below and spaced from the flanges 12 and 13 are formed inwardly extending shoulders 20 and 21. A hone 22 extends between the end pieces 10 and 11 and has its ends resting upon these shoulders, the hone acting as a compression member while the bolts 16 and 17 act as tension members to retain the parts rigidly in their assembled relation. As will be seen in Fig. 3, the upper surface of the hone is of concave, cylindrical shape, so that a double-edged safety razor blade, indicated in dotted lines at 24, may rest thereon with only its edges in contact with the hone, these edges contacting the hone at a predetermined angle depending upon the radius of curvature of the hone. If desired, the undersurface of the hone may be formed with a series of longitudinal grooves 26.

A slide 28 is reciprocably mounted in the frame below the hone 22, and is formed with opposite upwardly extending flanges 30 and 31, between which is mounted a permanent magnet 34. The magnet 34 is preferably of Alnico or similar composition, and is of sufficient strength to exert a considerable magnetic flux upon a magnetically permeable object, such as the blade 24, positioned at some distance from the magnet. The polarization of the magnet is such that the magnetic flux flows transversely of Fig. 3, so that if the north pole of the magnet is at the left of that figure, the south pole is at the right. In order to limit the reciprocatory movement of the slide, a pair of stop pins 36 and 37 are mounted in the end pieces 10 and 11 and project inwardly in such manner that at either extreme of the movement of the slide these pins will contact the flanges 30 or 31. As will be seen in Fig. 4, the magnet is of slightly shorter length than the remainder of the slide 28, to allow space for the projecting ends of these pins. The slide 28 is preferably formed with a lateral projection 40, of generally cylindrical shape, which is covered by a layer of leather 42, which may be used as a strop for completing the sharpening operation after the blade has been honed.

In the operation of this form of device, the user places a blade upon the hone in the position indicated in Fig. 1. He then holds the sharpener with one hand and places the thumb and forefinger of the other respectively against the projection 40 and the opposite edge of the slide, and reciprocates the slide. It is possible to reciprocate the slide rapidly in this manner so that the operation can be rapidly accomplished. As the slide with its magnet is reciprocated from one extreme position to the other, it draws the blade

24 along with it over the face of the hone, with the result that both edges of the blade are brought into frictional contact with the hone under a pressure which is substantially constant, being a function of the strength of the magnetic field and of the magnetic properties of the blade. As soon as the blade is placed upon the hone, the blade itself becomes magnetized, with a polarity opposite to that of the magnet. The blade is therefore constrained to at all times to move to a position wherein it forms part of a path for the lines of magnetic flux, and it is also pressed downwardly against the hone with a pressure which is uniform and which may be an optimum pressure if the instrument is properly designed with reference to the strength of the magnet and other factors. Another effect which the magnet has upon the blade is that because of the blade being magnetized, and because of the tendency of magnetically permeable material such as steel to move to such position as to minimize the length of the lines of magnetic force, the fine serrations at the edges of the blade are constrained to move into positions which lie in the plane of the blade, and thereby to align themselves with each other. This effect is facilitated by the agitation to which the blade is subjected during honing, and tends to produce an edge of unusually excellent cutting qualities. When the slide has reached the end of its stroke, inertia tends to cause the blade to continue its movement, but the force exerted by the magnet is sufficient to arrest it at either of the extreme positions shown in dotted lines in Fig. 2.

In the form of the invention shown in Figs. 1-4, the bolts 16 and 17 are preferably formed of steel or other magnetically permeable material, which forms part of the path of the magnetic flux and thereby increases the strength of the magnetic flux flowing through the blade. This increases the magnetization of the blade, and its tendency to follow the movement of the slide. In order to further increase this effect, the bolts may be formed of rectangular cross section as indicated at 46 and 47 in Fig. 5. The bolts in this figure are fitted closely against the edges of the hone, so as to form the shortest possible path for the magnetic flux. For the purpose of further increasing the magnetization, the hone, which is indicated at 48 in this figure, may be made relatively thin. The magnet, indicated at 50, is reciprocably mounted in a stationary tray or container 52, which comprises a bottom and end walls, all of which may be formed of plastic or other suitable material. The magnet is urged in one direction by a compression spring 54 which is seated in a recess formed in one of the side walls. For moving it in the opposite direction, a plunger 56 is reciprocably mounted in a bore in the opposite side wall, to be alternately actuated and released to cause the magnet, and thereby the blade (not shown in this figure) to be reciprocated relative to the hone 50.

In the further modified form of the invention shown in Fig. 6, the sharpener is made up of end pieces 69, which are similar to the end pieces 11 and 12 in Fig. 1, and are joined together by a bottom plate 62. Side walls 64, of magnetically permeable material, support the hone 66 at a distance above the bottom plate 62 and thereby form a slideway along which the magnet 68 is freely reciprocable. The parts 68, 62, 64 and 69 are secured together by adhesive or other suitable means. The magnet is reciprocated by simply reciprocating the sharpener, causing the magnet 75

to move by inertia from its one extreme position to the other and thereby move the blade over the hone.

Although the invention has been described with reference to certain particular embodiments thereof, it may be embodied in other forms within the skill of artisans in this art, and is not limited except in accordance with the terms of the following claims.

10 I claim:

1. A razor sharpener comprising a support, a non-magnetic element having a sharpening surface fixedly related to said support, and a magnet mounted in said support for reciprocation in a plane generally parallel to and in proximity to

15 said sharpening surface and capable of moving a magnetically permeable blade over said sharpening surface.

2. A razor sharpener comprising a frame, a hone fixedly mounted in said frame and having opposed longitudinal surfaces, one of said surfaces being of concave cylindrical form, the other of said surfaces being provided with longitudinal grooves, a slide reciprocably mounted adjacent said other surface, a permanent magnet carried by said slide and having its magnetic axis perpendicular to and spaced from the axis of the cylindrical surface, and means for limiting the extent of reciprocating movement of said slide.

30 3. The invention defined in claim 2, comprising in addition a pair of magnetically permeable members extending longitudinally of the hone adjacent the edges of said surfaces.

4. A razor sharpener comprising a frame, a sharpening member fixedly mounted in said frame and having opposite longitudinal surfaces one of which is of concave cylindrical form, and a magnet mounted in said frame for reciprocation in a direction perpendicular to the axis of said 35 one surface, said magnet having its magnetic axis extending in the direction of such reciprocation.

5. The invention defined in claim 4, comprising in addition a pair of magnetically permeable 45 members of rectangular cross section extending longitudinally of the sharpening member closely adjacent the edges of said surfaces.

6. The invention defined in claim 4, comprising in addition yielding means urging the magnet 50 in one direction along said axis, and manual means for moving the magnet in the opposite direction.

7. The invention defined in claim 4, wherein 55 said magnet is freely movable in either direction along said axis by reciprocation of the sharpener.

8. A razor sharpener comprising a member having a surface designed to sharpen a razor blade reciprocated thereon, frame means forming a slideway generally parallel to said surface, and a magnet reciprocably mounted in said slideway with its magnetic axis parallel to said surface and capable of moving a magnetically permeable razor blade resting on said surface.

9. A razor sharpener comprising a member 65 having a surface of concave cylindrical form designed to sharpen a razor blade reciprocated thereon, means including said member forming an enclosed slideway adjacent and generally parallel to said surface, and a magnet reciprocably mounted in said slideway with its magnetic axis perpendicular to the axis of said surface and capable of moving a magnetically permeable razor blade over said surface.
